UNITED STATES PATENT OFFICE.

TAKEO MIYAGI, OF WAIPAHU, TERRITORY OF HAWAII.

RAILWAY-BRAKE.

1,397,443.

Specification of Letters Patent. Patented Nov. 15, 1921.

Application filed January 8, 1921. Serial No. 435,871.

To all whom it may concern:

Be it known that I, TAKEO MIYAGI, a citizen of the Empire of Japan, residing at Waipahu, in the city of Honolulu and Territory of Hawaii, have invented new and useful Improvements in Railway-Brakes, of which the following is a specification.

One object of my present invention is the provision of a simple, easily installed and inexpensive brake apparatus possessed of the capacity of regulating the speed of the cars of a train conformably to that of the locomotive with a view to preventing bumping of the cars when the speed of the locomotive is slackened.

Other objects and practical advantages of the invention will be fully understood from the following description and claims when the same are read in connection with the drawings, forming part hereof, in which:

Figure 1 is a side elevation of a railway car equipped with the best practical embodiment of my invention of which I am cognizant.

Fig. 2 is an inverted plan of the same.

Fig. 3 is an enlarged detail plan of one of the couplers of the car.

Fig. 4 is a front elevation of the brake adjusting means.

Fig. 5 is a side elevation of the same.

Fig. 6 is a horizontal section taken through the brake adjusting means in the plane indicated by the line 6—6 of Fig. 7.

Fig. 7 is a vertical section taken in the plane indicated by the line 7—7 of Fig. 6.

Fig. 8 is a detail horizontal section as taken in the plane indicated by the line 8—8 of Fig. 7.

Fig. 9 is a detail plan view of the lever that is connected with the couplers.

Fig. 10 is a plan view of the lever that is connected with the brake shoes.

Fig. 11 is a plan view of the lever that is connected with the hand brake means.

Fig. 12 is a section taken through the emergency stop valve comprised in my invention; said section being taken on the line 12—12 of Fig. 13.

Fig. 13 is a section taken in the plane indicated by the line 13—13 of Fig. 12.

Fig. 14 is a section taken in the plane indicated by the line 14—14 of Fig. 12.

Similar letters and numerals of reference designate corresponding parts in all of the views of the drawings.

In furtherance of my invention I equip

the railway car A at its opposite ends with coupler heads 17, the said heads 17 being carried by drawer bars 15, outward endwise movement of which is resisted by springs 16. At their inner ends the drawer bars 15 are connected through the medium of links 14 with levers 13. Each of the levers 13 is fulcrumed at or about its center, and to the ends of the levers are connected rods 11 and 12.

Also in furtherance of my invention I arrange below the car body the brake adjusting means illustrated in detail in Figs. 4 to 14. The said brake adjusting means is bolted to the floor joist of the car body or is otherwise appropriately connected to the said body. It will be readily apparent that the said brake adjusting means comprises a train pipe 1, and a cylinder 19 in which is a rectilinearly movable piston 20. Through the train pipe 1 air or other fluid under pressure is supplied to a chamber 2; it being understood that the train pipe, as its name imports, is designed to extend throughout the length of a train and to be connected with means for supplying fluid under pressure. The chamber 2 is divided by a partition 3 into chamber sections, and the bottom of the chamber 2 is closed through the medium of a disk 4. Spaced from the said disk 4 is a plate or wall 10, and formed in the disk 4 and plate 10 are sector-shaped openings 5 and 6; the opening 5 in the disk 4 being coincident with the corresponding opening 5 in the plate 10, and the opening 6 in the disk 4 being coincident with the corresponding opening 6 in the plate 10. The disk 4 and the plate 10 are appropriately fixed with respect to the body of the brake adjusting means. Carried by the body of the brake adjusting means is a shaft 37 which extends loosely through the said disk 4 and plate 10, and interposed between the disk 4 and the plate 10 is a lever 7 in which are ports 8 and 9. This lever 7 is connected at or adjacent to its ends to the before-mentioned rods 11 and 12 that extend to the levers 13 in connection with the drawer bars 15 of the coupler head 17.

It will be understood from the foregoing that incident to the starting of a train the couplers of the car are subjected to endwise outward pull, with the result that the levers 13 are rocked about their axes. When the levers 13 are so rocked the lever 7 will be turned clockwise, with the result that the

openings 5 in the disk 4 will be closed, and the port 8 in the lever 7 will be moved into registration with the opening 6 in the disk 4. This will bring about the exhaust or discharge of the fluid under pressure from the cylinder 19 through the conduit 18, Fig. 7, the port 8 in the lever 7, the port 6 in the disk 4, the left-hand chamber section of the element 2, the conduit 21, Fig. 6, the air duct 22, Figs. 6 and 14, and the port 23 to the atmosphere. At the same time fluid under pressure is cut off from the cylinder 19 by reason of the port 5 being closed. It will be noticed in this connection that the train pipe 1 is connected by a branch pipe 1* with the chamber section 2 that is in communication with the port 5, and consequently when the port or opening 5 is closed no fluid under pressure can find its way to the cylinder 19 and hence the brakes will be released, with the result that the cars may be moved without interference.

In the event of the speed of the locomotive being reduced below the speed of the cars coupled to the locomotive the springs 16 operate to move the drawer bars 15 endwise inwardly and in consequence the levers 13 are rocked reversely to the before-described movement of the levers 13. Coincident with the rocking of the levers 13, when the drawer bars 15 are moved endwise inwardly, the lever 7 will be swung in anti-clockwise direction, whereupon the port 9 of the lever 7 will be registered with the ports 5 of the disk 4 and plate 10, the exhaust ports 6 of the disk 4 and plate 10 being at this time closed. In consequence of the last named positioning of the lever 7 fluid under pressure enters the cylinder 19 and operates to move the piston 20 toward the left in Fig. 7. Now it will be understood that the piston 20 is connected through the medium of a rod 24 with a swinging disk 25, and that when the piston is moved toward the left in Fig. 7 the movement of the disk 25 will be anti-clockwise. Incident to the turning of the disk 25 a lever 28, Figs. 7 and 10, is turned in the same direction as the disk 25, this being due to the fact that the disk 25 is provided with pendent pins 26 and 27, and that the said pins 26 and 27 are opposed to abutments 26* on the lever 28. The said swinging movement of the lever 28 will manifestly be attended by application of the brakes which are connected with the lever 28 through the medium of the rods 29 and 30, Figs. 2 and 10. The same operation will take place when the train is passing down a grade and when the cars have a tendency to overcome the locomotive.

As illustrated in Fig. 2, the car A is equipped with hand brakes 36. These hand brakes 36 are connected by rods 34 and 35, respectively, with a lever 31, Figs. 7 and 11. Therefore, when either of the hand brakes

36 is actuated the lever 31 will be swung in an anti-clockwise direction, and shoulders 31* on the lever 31 will operate against pendent pins 32 and 33 so as to turn the lever 28 in the same direction as the lever 31 and 70 seat the brakes; it being understood in this connection that the pins 32 and 33 depend from the lever 28.

When it is necessary to stop the car illustrated, or any car of a train equipped with my improvement, while the train is moving forwardly, the emergency stop valve illustrated in Figs. 12 to 14 is put into use. In this connection it will be understood that when the chain 47, shown in Fig. 1, is moved in the direction indicated by the arrow, a wheel 48, Fig. 1, will be turned in clockwise direction. The said wheel 48 is connected through the medium of a chain belt 47 with a disk 42, and when the wheel 48 is turned 80 in clockwise direction the disk 42 will be turned in the same direction until the duct 22 in said disk 42 is in registration with the port 40 and 44 of a disk 41, Figs. 12 and 14. At this time the exhaust conduit 21, Figs. 90 6 and 14, will be closed, and fluid under pressure from the train pipe 1 is free to pass through the conduit 40, the duct 22 and the pipe 44, Figs. 5 and 7, to the cylinder 19, so as to apply the brake in the same manner 95 as when the drawer bars 15 of the couplers are moved endwise inwardly.

It will be appreciated from the foregoing that my improvement provides for the automatic setting and release of the brakes, 100 and for the emergency setting of the brakes, all of which features contribute to the tractor of safety, as is desirable.

The construction as herein shown and described is for use when the locomotive is attached to the forward end of the train. When the locomotive is to be located at the rear end of a train for the purpose of pushing instead of pulling the train, I contemplate providing the train pipe 1 at a point 105 conveniently accessible by the engineer with an auxiliary stop valve similar to the valve shown in Fig. 14; the said auxiliary stop valve being so constructed and arranged that when the same is closed, fluid under pressure will be exhausted from the cylinder 19 and the supply of fluid under pressure to the cylinder 19 will be cut off, with the result that all of the brakes will be released.

Having described my invention, what I claim and desire to secure by Letters-Patent, is:—

1. In a railway brake, the combination of 125 brake shoes, rods connected therewith, a lever connected with said rods, a lever arranged in parallel relation to the first-named lever, one of said levers having pins and the other abutments opposed to the pins, a cylinder, a piston movable in the cylinder and 130

- connected with the second-named lever, a train pipe for fluid under pressure, means to establish communication between the train pipe and the cylinder to set the brake shoes against wheels, and movable control means to cut the cylinder off from the train pipe and establish communication between the brake cylinder and the atmosphere to release the brake shoes.
2. In a railway brake, the combination of brake shoes, rods connected therewith, a lever connected with said rods, a lever arranged in parallel relation to the first-named lever, one of said levers having pins and the other abutments opposed to the pins, a cylinder, a piston movable in the cylinder and connected with the second-named lever, a train pipe for fluid under pressure, means to establish communication between the train pipe and the cylinder to set the brake shoes against wheels, and movable control means to cut the cylinder off from the train pipe and establish communication between the brake cylinder and the atmosphere to release the brake shoes, with draw-bars, means connecting the draw-bars and said movable control means and arranged to move the latter for the supply of fluid under pressure to the cylinder when the draw-bars are relieved of pull, and to move the control means for the exhaust of fluid under pressure from the cylinder when the draw-bars are subjected to pull, and a manually-operable emergency valve adapted when actuated to bring about the supply of fluid under pressure to the cylinder and the application of the brake shoes.
3. In a railway brake, the combination of brake shoes, rods connected therewith, a lever connected with said rods, a lever arranged in parallel relation to the first-named lever, one of said levers having pins and the other abutments opposed to the pins, a cylinder, a piston movable in the cylinder and connected with the second-named lever, a train pipe for fluid under pressure, means to establish communication between the train pipe and the cylinder to set the brake shoes against wheels, and movable control means to cut the cylinder off from the train pipe and establish communication between the brake cylinder and the atmosphere to release the brake shoes, with draw-bars, means connecting the draw-bars and said movable control means and arranged to move the latter for the supply of fluid under pressure to the cylinder when the draw-bars are relieved of pull, and to move the control means for the exhaust of fluid under pressure from the cylinder when the draw-bars are subjected to pull, and to move the control means for the exhaust of fluid under pressure from the cylinder when the draw-bars are relieved of pull, and to move the control means for the exhaust of fluid under pressure from the cylinder when the draw-bars are subjected to pull.
4. In a railway brake, the combination of brake shoes, rods connected therewith, a lever connected with said rods, a lever arranged in parallel relation to the first-named lever, one of said levers having pins and the other abutments opposed to the pins, a cylinder, a piston movable in the cylinder and connected with the second-named lever, a train pipe for fluid under pressure, means to establish communication between the train pipe and the cylinder to set the brake shoes against wheels, and movable control means to cut the cylinder off from the train pipe and establish communication between the brake cylinder and the atmosphere to release the brake shoes, with draw-bars, means connecting the draw-bars and said movable control means and arranged to move the latter for the supply of fluid under pressure to the cylinder when the draw-bars are relieved of pull, and to move the control means for the exhaust of fluid under pressure from the cylinder when the draw-bars are subjected to pull, and to move the control means for the exhaust of fluid under pressure from the cylinder when the draw-bars are relieved of pull, and to move the control means for the exhaust of fluid under pressure from the cylinder when the draw-bars are subjected to pull.
5. In a railway brake, the combination of brake shoes, rods connected therewith, a lever connected with said rods, a lever arranged in parallel relation to the first-named lever, one of said levers having pins and the other abutments opposed to the pins, a cylinder, a piston movable in the cylinder and connected with the second-named lever, a train pipe for fluid under pressure, means to establish communication between the train pipe and the cylinder to set the brake shoes against wheels, and movable control means to cut the cylinder off from the train pipe and establish communication between the brake cylinder and the atmosphere to release the brake shoes, with draw-bars, means connecting the draw-bars and said movable control means and arranged to move the latter for the supply of fluid under pressure to the cylinder when the draw-bars are relieved of pull, and to move the control means for the exhaust of fluid under pressure from the cylinder when the draw-bars are subjected to pull, and to move the control means for the exhaust of fluid under pressure from the cylinder when the draw-bars are relieved of pull, and to move the control means for the exhaust of fluid under pressure from the cylinder when the draw-bars are subjected to pull.
6. Fluid pressure brake control means comprising a train pipe, a cylinder, a piston movable in the cylinder and adapted to be connected with a movable brake shoe, movable draft means, and movable means controlled by movement of the draft means to establish communication between the train pipe and the cylinder when the draft means is relieved of pull and to cut off said communication and establish communication between the cylinder and the atmosphere when the draft means is subjected to pull.
7. Fluid pressure brake control means comprising a train pipe, a cylinder, a piston movable in the cylinder and adapted to be connected with a movable brake shoe, movable draft means, and movable means controlled by movement of the draft means to establish communication between the train pipe and the cylinder when the draft means is relieved of pull and to cut off said communication and establish communication between the cylinder and the atmosphere when the draft means is subjected to pull.

- connected with a movable brake shoe, movable draft means, and movable means controlled by movement of the draft means to establish communication between the train pipe and the cylinder when the draft means is relieved of pull and to cut off said communication and establish communication between the cylinder and the atmosphere when the draft means is subjected to pull, in combination with manually-operable emergency means to cut off communication between the cylinder and the atmosphere and to establish communication between the train pipe and the cylinder.
- 15 8. Fluid pressure railway brake means comprising a train pipe, a cylinder, a piston movable in the cylinder and adapted to be connected with a movable brake shoe, movable draft means, and movable means controlled by movement of the draft means to establish communication between the train pipe and the cylinder when the draft means is relieved of pull and to cut off said communication and establish communication between the cylinder and the atmosphere when the draft means is subjected to pull, in combination with manually-operable emergency means to cut off communication between the cylinder and the atmosphere and to establish communication between the train pipe and the cylinder, and manually-operable means to apply the brake shoe mechanically and independently of the fluid pressure means.
- 30 9. Fluid pressure railway brake means comprising a train pipe, a cylinder, a piston therein, movable draft means, chamber sections, a conduit between the train pipe and one of said chamber sections, a conduit leading to the cylinder, an exhaust conduit, and a lever connected with and movable by the draft means to establish in one position communication between the train pipe and the cylinder and to establish in another position communication between the cylinder and the atmosphere, in combination with a manually-operable valve to establish communication between the train pipe and the cylinder, a manually-operable lever, and a lever included in a connection between the piston and a brake shoe and arranged to be moved by said manually-operable lever.
- 45 10. Fluid pressure railway brake means comprising a train pipe, a cylinder, a piston therein, movable draft means, chamber sec-

tions, a conduit between the train pipe and one of said chamber sections, a conduit leading to the cylinder, an exhaust conduit, and a lever connected with and movable by the draft means to establish in one position communication between the train pipe and the cylinder and to establish in another position communication between the cylinder and the atmosphere, in combination with a manually-operable valve to establish communication between the train pipe and the cylinder.

11. Fluid pressure railway brake means comprising a train pipe, a cylinder, a piston therein, movable draft means, chamber sections, a conduit between the train pipe and one of said chamber sections, a conduit leading to the cylinder, an exhaust conduit, and a lever connected with and movable by the draft means to establish in one position communication between the train pipe and the cylinder and to establish in another position communication between the cylinder and the atmosphere, in combination with a manually-operable lever, and a lever included in a connection between the piston and a brake shoe and arranged to be moved by said manually-operable lever.

12. Fluid pressure railway brake means comprising a train pipe, a cylinder, a piston therein, movable draft means, chamber sections, a conduit between the train pipe and one of said chamber sections, a conduit leading to the cylinder, an exhaust conduit, and a lever connected with and movable by the draft means to establish in one position communication between the train pipe and the cylinder and to establish in another position communication between the cylinder and the atmosphere, in combination with a manually-operable valve to establish communication between the train pipe and the cylinder, a manually-operable lever, and a lever included in a connection between the piston and a brake shoe and arranged to be moved by said manually-operable lever.

In testimony whereof I affix my signature.

TAKEO MIYAGI.
